COMBINATION BLOUSE AND SLIP

Sidney A. Wiesenfeld, Brooklyn, N. Y.

Application October 12, 1950, Serial No. 189,770

3 Claims. (Cl. 2—73)

1

This invention relates to a combination blouse and slip.

It is an object of the present invention to provide a combination blouse and slip wherein adequate means are provided between the sides of the blouse and at the rear of the slip portion to draw the blouse around the front of the wearer and wherein the back of the blouse is loose fitted over the back of the wearer and downwardly over the slip so as to allow freedom of movement between the back of the blouse and the slip portion upon the wearer bending over and wherein there is sufficient play on the back of the slip portion to permit the easy pull of the garment over the wearer.

Other objects of the present invention are to provide a combination blouse and slip of the type above described which is of simple construction, inexpensive to manufacture, has a minimum number of parts, of pleasing appearance and efficient in use.

For other objects and for a better understanding of the invention, reference may be had to the following detailed description taken in connection with the accompanying drawing, in which

Fig. 1 is a perspective view of the combination blouse and slip embodying the features of the present invention and as viewed from the front of the garment.

Fig. 2 is a perspective view of the garment as viewed from the rear thereof with the rear of the blouse lifted to show the manner in which the upper part of the slip portion extends about the back and the manner in which the front of the blouse is pulled at the sides.

Fig. 3 is a transverse sectional view taken on line 3—3 of Fig. 1.

Fig. 4 is a vertical sectional view taken on line 4—4 of Fig. 1.

Fig. 5 is a perspective view looking upon the rear of the garment constructed according to a modified form of the invention wherein the back of the blouse has button portions which may be separated and the rear portion of the slip is provided with a slide fastener to draw the slip and the front of the blouse tight about the wearer.

Fig. 6 is a rear elevational view of a still further form of the garment and similar to Fig. 5, but where a hook and eye arrangement is used for tightening the slip portion upon the wearer.

Fig. 7 is a collective view of a still further form of the invention wherein the parts are separable from one another and are connected by means of buttons disposed about one of the parts with 53 opposite sides of the slit being joined together.

2

the other part having button openings for receiving the buttons, the rear portion of the blouse being longer than the front portion so as to extend well below the waistline of the wearer.

Referring now particularly to Figs. 1 to 3, 10 represents a blouse portion having a front panel 11 and a rear panel 12. These panels are connected together at the shoulders, as indicated at 13, and sleeves 14 and 15 depend from the sides thereof. Connected to the blouse 10 is a slip part 16 having a front panel 17 that is stitched to the front panel 11 of the blouse part 10, as indicated at 18. This slip part has a back panel 19 that is cut longer and extends upwardly above the front panel 17 of the slip portion, as shown in Fig. 2, and is secured to the sides of the front panel 11 of the blouse part. The lower end of the back panel 12 is broken away from the sides of the front panel so as to be loose and to permit the wearer to bend freely without pulling upon the slip part. The upper edge of the back panel contains an elastic 20 which will gather the upper edge of the back portion of the slip part and will draw the front panel of the blouse part about the waist of the wearer. The lower end of the back panel 12 provides a flap and is tucked under the skirt.

In Fig. 5, there is shown a still further form of the invention wherein the back of the blouse part is separable along the middle thereof and is secured by buttons 22. A front panel 23 is secured by a slide fastener arrangement 24 to a front panel 25 of a slip part whereby the blouse can be detached from the slip part. This slide fastener arrangement extends straight across the lower end of the front panel of the blouse and upwardly at the sides of the front panel of the blouse. A rear panel 26 of the slip part extends upwardly above the upper edge of the front panel of the slip part to lie across the back of the wearer and is split, as indicated at 27, to provide for a slide fastener arrangement 28 which can be pulled upwardly to tighten the slip part about the wearer and to pull the front panel of the blouse about the waist of the wearer.

In Fig. 6, there is shown a still further form of the invention. In this form of the invention the blouse has separable back portions, as indicated at 31 and 32, which are joined by buttons 33 fitting into button hole openings 34. The front panels of the blouse and slip may be fixed to each other or separable, in the manner as shown in Fig. 5. Slip 35 is slit, as indicated at 36, and is tightened by a hook 37 and an eye 38 on the 50 opposite sides of the slit being joined together.

In Fig. 7, there is shown a still further form of the invention where there are separable blouse and slip parts. Blouse part 41 has a front panel 42 and a drop rear panel 43. The rear panel 43 of the blouse part 41 is dropped in such a manner as to provide a flap over the rear panel of the slip. The front panel 42 has button hole openings 45 which are connected to buttons 46 of front panel 47 of the slip part 48. Rear portion 49 is elevated above front panel 47 of the blouse part and will extend under the rear panel 43 of the blouse part. Elevated buttons 51 on the rear panel of the slip part will engage with side button hole openings 52 on the blouse part. It will be seen that these parts are easily detachable and that there is provision so that the rear panel of the blouse part can permit the wearer to bend or stoop over.

It will be apparent that there has been provided, according to the various forms of the invention, a combined blouse and slip and where, if desired, the blouse and slip can be separated from one another, yet when connected to one another they form a unitary garment where the back panel of the blouse is free to be worked under the skirt and wherein adequate means is provided for drawing the front panel of the blouse around the waist of the wearer. The different parts of the garment will be made of the usual material which is used for the making of these parts. The blouse will be made of the usual outside wear material whereas the slip part will be formed of the usual inner garment material. The wearer can bend or raise arms overhead without hiking up the slip in the rear. The slip is not joined to the blouse in the rear but has means for tightening the rear portion of the slip upon the wearer.

While various changes may be made in the detail construction, it shall be understood that such changes shall be within the spirit and scope of the present invention as defined by the appended claims.

What is claimed is:

1. A combined blouse and slip comprising a blouse part having front and rear panels adapted to extend below the waistline of the wearer, a slip part having front and rear panels, said rear

panel of the slip part extending above the front panel of the slip part and to the waistline and adapted to lie under the rear panel of the blouse part, said rear panel of the blouse part being free at its lower end to serve as a flap to lie over the rear panel of the slip part, the lower edge of the front panel of the blouse part being secured to the upper edge of the front panel of the slip part, the upper side edges of the rear panel of the slip part being secured to the lower side edges of the front panel of the blouse part.

2. A combined blouse and slip as defined in claim 1 and means on the upper edge of the rear panel of the slip part for drawing the front of the blouse about the waistline of the wearer.

3. A combined blouse and slip comprising a blouse part having front and rear panels, adapted to extend below the waistline of the wearer, a slip part having front and rear panels, said rear panel of the slip part extending above the front panel of the slip part and to the waistline and adapted to lie under the rear panel of the blouse part, said rear panel of the blouse part being free at its lower end to serve as a flap to lie over the rear panel of the slip part, the lower edge of the front panel of the blouse part being detachably secured to the upper edge of the front panel of the slip part, the upper side edges of the rear panel of the slip part being detachably secured to the lower side of the front panel of the blouse part.
